ELECTRONIC INSTRUCTIONAL CONSOLE

George R. Dean, Chicago, James B. Ricks, Evanston, and
 David D. Dalenberg, Lombard, Ill., assignors to Bell &
 Howell Company, Chicago, Ill.

Filed Feb. 25, 1974, Ser. No. 445,386

Term of patent 14 years

Int. Cl. D19—07

U.S. Cl. D19—60

FIG. 1 is a front perspective view of an electronic instructional console showing our new design.

FIG. 2 is an elevation view showing the rear of the console.

The side not seen in FIG. 1 is substantially the same as that shown.

We claim:

The ornamental design for an electronic instructional console, substantially as shown and described.
